LINK MECHANISM FOR PRESSURE CASTING
MACHINESNathan Lester, Shaker Heights, Ohio, assignor to
Lester Engineering Company, Cleveland, Ohio,
a corporation of Ohio

Application February 13, 1946, Serial No. 647,259

4 Claims. (Cl. 74—110)

1

The present invention relates to improvements in a link mechanism for imparting the final high pressure closing movement to the die plates of a pressure casting machine. In such machines the die plates carry the mold members or die blocks in which the mold cavity is formed when such die plates are in closed position and into which cavity the material to be cast is forced under very high pressure. The die plates must therefore be held in a closed position under a relatively great force which is sufficient to withstand the casting pressure tending to open them. Heretofore, toggle link mechanisms having wedge means associated therewith have been utilized to acquire this high pressure final closing movement. However, in these prior devices the wedge means have been usually engaged only in line contact with one another except at the last instant of the final closing movement, at which time they finally engage in surface contact with one another. Thus, even small forces applied through these wedge means prior to the last instant of the final closing movement impart extremely high unit stresses in the engaging portions of the wedge means with the result that the wedge means will be deformed or will score or seize with one another or otherwise be rendered inefficient.

It is one of the principal objects of this invention to provide in such a toggle link mechanism wedge means which, when engaged, continuously engage one another in surface contact during the entire final closing movement, thereby materially reducing the unit stresses on the wedge means and thus minimizing the damage to the wedge means and also permitting application of much greater forces during the final closing movement.

Another object of this invention is to provide means wherein the area of surface contact between the wedge means increases as the closing force on the die plates increases.

Another object of this invention is to provide simple means for accomplishing the aforesaid continuous surface contact without requiring the use of complex universally mounted wedge means.

Additional objects and advantages of the invention will become apparent as the following description proceeds.

To the accomplishment of the foregoing and related ends, said invention then comprises the features hereinafter fully described and particu-

2

larly pointed out in the claims, the following description and the annexed drawings setting forth in detail certain illustrative embodiments of the invention, these being indicative, however, of but a few of the various ways in which the principle of the invention may be employed.

In the drawings:

Fig. 1 is a front elevation view partly in vertical section of that portion of a pressure casting machine containing the die plate actuating mechanism, such mechanism having been operated to fully close the die plates;

Fig. 2 is similar to Fig. 1 except that the die plate actuating mechanism has been operated to fully open the die plates;

Fig. 3 is a vertical cross section of the actuating mechanism taken along line 3—3 of Fig. 1;

Fig. 4 is a plan view of the actuating mechanism as viewed from the top of Fig. 1;

Figs. 5 and 6 are enlarged views partially schematic of the link mechanism just prior to commencement of the final closing movement of the die plates, and at the last instant of the final closing movement, respectively; and

Fig. 7 is a schematic enlarged view of the link mechanism clearly showing the relationship between the wedge means of the link mechanism for accomplishing the objects of this invention.

Referring now to the drawings, the machine as a whole includes a frame 1 which reciprocably carries a die plate 2 and which die plate, as is well known to those skilled in the art, carries a die block engageable and disengageable with a die block and die plate, not shown, fixedly mounted on the frame 1. Reciprocating movement of the die plate 2 is effected by means of a hydraulic piston and cylinder assembly 3 having the piston rod portion 6 connected thereto. The piston and cylinder assembly 3 is provided with passages 4 and 5 and by means of suitable valves, not shown, fluid under pressure can be directed at will to either end of the cylinder to move the piston therein in opposite directions. The connection of piston rod 6 to the die plate 2 is effected through a toggle link mechanism which linkage is arranged in cooperation with the frame 1 to effect movement of the piston rod and die plate rapidly in unison during the opening and closing movements, but with very great relative movement during the final closing and initial opening move-

ments to attain the great mechanical advantage necessary in order to effect final closing of the die plates with very high pressure.

The toggle linkage comprises links 7 and 8 pivotally connected to one another and to the piston rod 6 and die plate 2, respectively. As shown, one end of each link 7 is pivotally connected to the die plate 2 about a pivot pin 9 which passes through the link 7 and through the spaced ear portions 10 on the die plate. Each of the ear portions 10 has a hardened metal insert 11 secured thereto in engagement with a hardened metal insert 12 secured to each link 7. The faces of inserts 11 and 12 which are in engagement with one another are cylindriform with each pivot pin 9 as an axis. As will become more apparent as the description proceeds, a shearing stress on the pins 9 will be relieved or limited by the bearing or compression stress taken up by the engagement of these inserts with one another. Each link 7 has a laterally projecting leg 13 thereon, the end of which is engageable with a corresponding leg on the other link 7 to limit the pivotal movement of the links 7 toward one another. Each link 7 is also provided with two shelf portions 14, slidably engageable with corresponding shelf portions 14 in the frame 1. A wear strip 15 is secured to each shelf 14 to take up the wear between the shelf portions of the links 7 and the frame 1.

A plurality of links 8 are pivotally connected about pivot pins 17 and 18 to the links 7 and to a head 16, respectively, which head is secured to the piston rod. Hardened metal inserts 20 between the links 7 and 8 operate to relieve or limit the shearing stress on pins 17 as described above in relation to pin 9 and inserts 11 and 12.

Secured to frame 1 and to the outer ends of links 7 are hardened metal wedge inserts 21 and 22, respectively. For the present, let it suffice to say that as the links 7 are swung outwardly about pins 9, the inserts 21 and 22 will engage one another to effect relative movement between the frame 1 and the die plate 2.

As for the general operation of the toggle linkage, let us assume that die plate 2 is fully opened as shown in Fig. 2. In this position links 7 are collapsed inwardly with legs 19 thereof in engagement and with the shelf portions 14 of the links in engagement with the shelf portions 14 in the frame 1. Now, if it be desired to move the die plate 2 toward the right to a closed position into engagement with the other die plate, not shown, piston rod 6 is caused to be moved toward the right. In so doing, the piston rod 6 and die plate 2 will move in unison by reason of the fact that links 7 are constrained by the shelf portions 14 from being swung outwardly by the force applied to the links 8. However, as soon as the die plate 2 lightly engages the other die plate and the shelf portions 13 and 14 disengage from one another and the inserts 21 and 22 are in the position shown in Fig. 5, further movement of the piston rod 6 toward the right will, through the links 8, cause the links 7 to be swung outwardly. As the links 7 swing outwardly, the inserts 21 and 22 will engage one another and the die plate 2 will be caused to partake of its final high pressure closing movement, the force of which attains a maximum when the links 8 are in alignment. When the links 8 are in alignment, the reaction through the inserts 21 and 22 will exert a very high closing force on the die plate 2. The final closed position of the die plate is attained when the links 7 and 8 bear relation

to one another, as shown in Figs. 1 and 6. In Fig. 6, the distance through which die plate 2 has been moved relative to the frame 1 during the final closing movement is indicated by the dimension line 30.

To clearly set forth the principal feature of this invention, reference will now be made primarily to Fig. 7 and also to Figs. 5 and 6 which schematically show the relation of the surfaces of the inserts 21 and 22 to one another and to the axis of pin 9. Inasmuch as the movement between frame 1 and die plate 2 is relative, the following description, in order to simplify and clarify the same, will proceed on the assumption that frame 1 is movable and that die plate 2 is fixed. When the inserts 21 and 22 are in the position shown in Fig. 5 and as shown in full lines in Fig. 7, the axes 23 of the cylindrical faces 24 and 25 of the inserts are coincident but eccentric of the axis 26 of pin 9. The relative movement between frame 1 and the die plate is indicated in amount and direction by the dimension 27 and the straight line 28. Thus, at the attainment of the final closing movement, axis 23 will have moved to position A. Now, in order that surface 25 will engage surface 24 in surface contact as the link 7 rotates about axis 26, it is necessary that axis 23 of surface 25 always be coincident with axis 23 of surface 24. From a theoretic standpoint, this can be accomplished only by moving axis 23 of surface 25 in a straight line 28 as does the axis 23 of surface 24. However, from a practical standpoint, such can be satisfactorily accomplished by selecting the axis 26 along a line 33 which is the perpendicular bisector of the line 28. In such case, axis 23 of surface 25 will move in a circular path 29 of radius equal to the eccentricity of the axis 23 with respect to the axis 26, as the link 7 is rotated about axis 26. For small amounts of relative movement, the circular path 29 will at all times between the limits of line 28 be so nearly straight that for all practical purposes, axes 23 of the surfaces 24 and 25 will be coincident during movement of the insert 22 from the solid line position to the dotted line position. Naturally, as the ratio of the eccentricity to the amount of relative movement approaches infinity, the path of the axis which describes a circular path will approach a straight line path.

In an actual machine, the relative movement during the final closing movement is on the order of only several thousandths of an inch and therefore the error due to the theoretical non-coincidence of the axes 23 can be disregarded and it can be considered, as a practical matter, that surface 25 will engage surface 24 in surface contact throughout its movement from the solid line position to the dotted line position of Fig. 7. Thus, it will be seen that as the closing force increases, the area of surfaces 24 and 25 in contact likewise increases and because there is surface contact, as distinguished from line contact, much greater forces can be transmitted to the die plate 2 without causing damage or excess wear to the inserts 21 and 22.

Other modes of applying the principle of the invention may be employed, change being made as regards the details described, provided the features stated in any of the following claims or the equivalent of such be employed and while described with particular reference to its use in a pressure casting machine, it will be understood that my improved link mechanism may be used in conjunction with any machine or device

wherein it is desired to impart high pressure relative movement between two relatively movable members.

I therefore particularly point out and distinctly claim as my invention:

1. In a linkage mechanism for pressure casting machines and the like, the combination with two relatively movable members of a link pivotally connected to one of said members for swinging movement into abutting engagement with the other of said members, said link and other member being formed with abutting cylindrical surfaces bearing fixed relation to said link and other member respectively, the axes of such surfaces being disposed eccentrically of the pivot axis of said link and coinciding during swinging movement of said link as aforesaid.

2. In a linkage mechanism for pressure casting machines and the like, the combination with two relatively movable members of a link pivotally connected to one of said members for swinging movement into abutting engagement with the other of said members, said link and other member being formed with abutting cylindrical surfaces bearing fixed relation to said link and other member respectively, the axes of such surfaces being disposed eccentrically of the pivot axis of said link and coinciding during swinging movement of said link as aforesaid, the pivot axis of said link lying on a line perpendicularly bisecting the line of relative movement of said members effected by swinging of said link as measured by the line of movement of the axes of the abutting surfaces of said link and other member relative to the pivot axis of said link.

3. In a linkage mechanism for pressure casting machines and the like, the combination with two relatively movable members of a link pivotally connected to one of said members for swinging movement to a wedged position between said members, said link and the other of said members

being formed with abutting cylindrical surfaces bearing fixed relation to said link and other member respectively, the axes of such surfaces being eccentric of the pivot axis of said link and coinciding when said link is in a position with its cylindrical surface adjacent that of said other member and during movement of said link to a wedged position between said members.

4. In a linkage mechanism for pressure casting machines and the like, the combination with two relatively movable members of a link pivotally connected to one of said members for swinging movement to a wedged position between said members, said link and the other of said members being formed with abutting cylindrical surfaces bearing fixed relation to said link and other member respectively, the axes of such surfaces being eccentric of the pivot axis of said link and coinciding when said link is in a position with its cylindrical surface adjacent that of said other member and during movement of said link to a wedged position between said members, the pivot axis of said link lying on a line perpendicularly bisecting the line of relative movement of said members effected by swinging of said link from a position with its cylindrical surface adjacent that of said other member to a position wherein said link is wedged between said members.
